UNITED STATES PATENT OFFICE.

JOHN A. ERICKSON, OF EAST LANSING, MICHIGAN.

MOLD FOR TILE.

Application filed September 9, 1927. Serial No. 218,451.

This invention relates to a mold for making concrete blocks and while the mold may be used to make blocks of various types, it particularly is designed for use in making 5 hollow blocks having inwardly extending flanges about the openings therethrough. In such blocks the cross section of the cavity in the block at its largest part is of greater area than the openings in the ends 10 of the block. It is therefore impossible to have a core of fixed dimensions which can be drawn through one of said openings. A collapsible core is thus necessary. If a collapsible core is used, which is drawn directly 15 away from the material of the block, the said material is very apt to stick to the core and be pulled away therewith, so that holes and rough places are formed in the block.

It is an object of this invention, therefore, 20 to provide a mold having an outer casing and a collapsible core, which core comprises members having surfaces engaging the inner side of the block and which are moved to collapsed position with a wiping or sliding movement over the inner side of the 25 block.

It is another object of this invention to provide a mold for concrete block having a 30 core comprising members having fixed surfaces at opposite sides of the block and having movable collapsible members at the other opposite sides of the block adapted to swing inwardly within the outlines of said first mentioned members.

It is still another object of the invention 35 to provide a mold for a concrete block having a core comprising walls with fixed surfaces at opposite sides of the block which are movable rectilinearly through the openings in the block and having members at the opposite sides of the block comprising bars having surfaces meeting substantially at the central part of the block to form walls of the core, said latter surfaces being convex 40 and curving inwardly toward the openings in the sides of the block, together with means for swinging said portions inwardly with a wiping movement over the inner surfaces of the block, to move the same within 45 said first mentioned walls so as to be moved out of the block therewith.

It is still another object of the invention 50 to provide a mold having a collapsible core having walls at opposite sides of the block, movable out of the same through the openings in the block, and walls at the other op-

posite sides of the block formed by collapsing members extending beyond said first mentioned walls substantially parallel thereto, together with a member for withdrawing said first mentioned walls connected to said members by toggle links whereby said members are collapsed within the outlines of said first mentioned wall and withdrawn therewith.

These and other objects and advantages 60 of the invention will be fully set forth in the following description made in connection with the accompanying drawings, in which like reference characters refer to similar parts throughout the several views and in which:

Fig. 1 is a perspective view partly in vertical section illustrating the mold;

Fig. 2 is a transverse vertical section 75 through the mold taken substantially on line 2—2 of Fig. 1;

Fig. 3 is a view similar to Fig. 2, showing the core of the mold collapsed and partially withdrawn;

Fig. 4 is a vertical section taken on line 4—4 of Fig. 2;

Fig. 5 is a horizontal section taken on line 5—5 of Fig. 2; and

Fig. 6 is a view in perspective of one of 80 the blocks used, and showing another block in vertical section.

Referring to the drawings, a model is shown comprising an outer casing 10 and while this casing may be of various shapes, in the embodiment of the invention illustrated it is shown as of rectangular shape, the same having the inwardly extending top and bottom flanges 10^a extending thereabout. A platen 11 is disposed within the lower portion of casing 10, adapted to be elevated or moved relatively to casing 10 by the bars 12. The mold has a core comprising walls 13 at opposite sides thereof, which, in the embodiment of the invention illustrated, are shown as disposed at the smaller sides or ends of the mold. The walls 13 are connected at their upper portions by the top wall or plate 13^a, which has beveled sides 13^b as shown. The walls 13 have slots 13^c in which move slotted members 14. The members 14 are pivotally connected at their lower ends to an operating lever 15 pivoted intermediately 90 the members 14 to a fixed standard 16, said lever 15 extending at one side of one of the members 14. While the members 14 may be variously formed to connect to the lever 15,

in the embodiment of the invention illustrated they are shown as being twisted through 90° at their lower ends for such attachment. The walls 13 also have extending therebetween at their lower corners the strips 17. Shafts 18 extend between and have their ends fixed in the walls 13. Oscillatably mounted on the shafts 18 are pairs of members 19 and 20. The members 19 and 20 at each side of the core form a wall thereof, and in the embodiment of the invention illustrated, these members form the longer or side wall. The outer surfaces of the members 19 as shown, curve upwardly and inwardly, and have their upper inner edges substantially in contact with the lower edge of the sides 13^b when the core is in extended position as shown in Fig. 2. The outer surfaces of the member 20 curve downwardly and inwardly and have their end edges substantially in contact with the edges of the strips 17 when the core is in extended position as shown in Fig. 2. The portions of the surfaces of members 19 and 20 at the central part of the core are substantially plane, and the edges of these surfaces meet in a line disposed substantially at the central part of the core or block. The members 19 at their sides have upwardly extending arms 19^a and these arms are connected at opposite ends of said members respectively by links 21 to one of the members 14, the upper end of said members 14 being offset inwardly as shown in Fig. 1. The members 20 have downwardly extending arms 20^a and these arms at opposite ends of said members respectively are also connected by links 22 to one of the members 14. The members 19 and 20 also have end surfaces 19^b and 19^c which project beyond the sides of the walls 13. These end surfaces on the members 19 and 20 also meet in a line in the same plane as the meeting line of the side surfaces of said members.

In operation, the mold will be disposed in the position shown in Figs. 1 and 2. The material will be placed between the casing 10 and the outer surfaces of the core formed by walls 13 and members 19 and 20. It will be seen that an enclosed space is formed, which, when filled with concrete, forms the block 23, the block resting on the platens 11. It will be seen that the block has inwardly extending flanges 23^a at top and bottom which surround the openings in the top and bottom thereof. When the block is to be removed from the mold, the lever 15 is swung about its pivotal connection with the standard 16 and one of the members 14 is moved upwardly and the other moved downwardly. The member moving downwardly swings the links 21 downwardly and through the arms 19^a, swings the members 19 inwardly about shafts 18 so that they assume the position shown in Fig. 3. The other member 14

swings the links 22 upwardly so that through arms 20^a the members 20 are also swung inwardly to the position shown in Fig. 3. The directions of movement of members 19 and 20 in the collapsing of the core is indicated by the arrows in Fig. 2. When the members 19 and 20 are in their inward or collapsed positions, they are within the outlines of the walls 13 as shown in Fig. 3. The members 12 are then elevated by suitable mechanism and the platens 11 are raised, thus removing the block from casing 10 and moving the same over the collapsed core as shown in Fig. 3. When another block is to be made, the lever 15 is swung in the opposite direction and the members 19 and 20 are then swung outwardly in the directions indicated by the arrows in Fig. 3, so that these members assume the positions shown in Fig. 2, the platens 11 being returned to position shown, so that the mold is again in position to receive a block. It will be noted that when the members 19 and 20 are moved to collapsed position, they swing in an arc and the outer surfaces thereof move over the inner surfaces of the block or of the concrete with a sliding or wiping action. The links 21 and 22 form pairs of toggles holding the members 19 and 20 in expanded position. This action is similar to that of a trowel and with such an action there is no danger of the concrete being pulled away from the block by sticking to the core. A smooth and clean surface is thus left on the inner side of the block after the core is collapsed.

The shape of the block made is clearly shown in the drawings, particularly Fig. 6. It will be seen that there is an offset at the ends of the block between the surfaces made by the outer side of the walls 13 and the end surfaces of members 19 and 20.

From the above description it is seen that applicant has provided a very simple and very efficient mold for concrete or cement blocks. The mold has a collapsing core which is moved to collapsing position by a wiping action so that no material is pulled away from the inner side of the block. The mechanism is very simple in construction and easily and quickly operated. The device has been demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:

1. A mold for a hollow concrete block having in combination, an outer casing, a

core comprising inwardly collapsing walls and means for moving said walls to collapsed position with a sliding movement over the inner surface of the block.

5 2. A mold for a hollow concrete block having in combination, an outer casing, a core comprising inwardly collapsing walls having curved convex surfaces engaging the inner side of said block, and means for 10 swinging said walls inwardly to collapsed position with a wiping movement over the inner side of said block.

3. A mold for a hollow concrete block having in combination, an outer casing, a 15 core having inwardly collapsing walls at opposite sides of said mold, comprising members having surfaces meeting substantially at the center of the block and curved inwardly toward the opposite surfaces of the 20 block to form flanges on said block, and walls at the other opposite sides of said block within which said members are collapsed, and means for swinging said members inwardly to collapsed position in a 25 curved path.

4. A mold for a hollow concrete block having in combination, an outer casing, a core comprising walls at opposite sides of said block movable rectilinearly from said block, and members extending beyond said walls at the other opposite sides of said block to form flanges at opposite sides of said block, said members also having surfaces parallel to said first mentioned surfaces engaging said block, and means for swinging said members inwardly within the outlines of said walls whereby the block and core may be relatively moved rectilinearly.

5. A mold for a hollow concrete block 40 having in combination, an outer casing, a core comprising end walls with fixed surfaces, members forming side walls of said core having portions with surfaces meeting at substantially the center of said core, said 45 portions of each member being pivoted about a common axis to swing in opposite directions, and means for swinging said portions

to collapsed position within the sides of said end walls.

6. A mold for a hollow concrete block 50 having in combination, an outer casing, a collapsible core comprising end walls with fixed surfaces, spaced shafts extending between said end walls and collapsible side walls, each comprising a plurality of portions journaled on said shafts and swingable thereon in opposite directions, means for swinging said portions inwardly within the outlines of said end walls to move the same to collapsed position, said means comprising 55 a vertically movable member, and links connecting the same to said portions.

7. A mold for a hollow concrete block having in combination, an outer casing, a core comprising rectilinearly movable walls at 65 opposite ends thereof, said walls being substantially rectangular in shape, supporting means carried by said walls and collapsible walls swingingly mounted on said supporting means, said collapsible walls comprising 70 separable sections having outer surfaces curved inwardly toward opposite surfaces of said block and having inwardly extending arms, members movable vertically adjacent said first mentioned walls and links connected to said members respectively and to said arms, said links adapted to form a toggle to hold said collapsible core in expanded position.

8. The structure set forth in claim 7, a 75 top member for said core extending between said first mentioned walls and contacting said collapsible core when in expanded position.

9. The structure set forth in claim 7, a 80 top member extending between said first mentioned walls and between the tops of said collapsible walls and engaging the latter, and spaced members extending between said end walls and engaging the bottom of 90 said collapsible walls.

In testimony whereof I affix my signature.

J. A. ERICKSON.
